DESIGN FOR A GOLF CLUB

Application filed December 10, 1931. Serial No. 42,025. Term of patent 7 years.

To all whom it may concern:

Be it known that we, THOMAS DOBSON and CHARLES B. JOHNSON, citizens of the United States, residing at Milwaukee, in the county of Milwaukee and State of Wisconsin, have invented a new, original, and ornamental Design for Golf Clubs, of which the following is a specification, reference being had to the accompanying drawings, forming a part thereof.

As will be understood from the drawings, the characteristic feature of the design is the formation of the hosel and the portion of the shaft connected thereto. These parts are so fashioned that their exterior consists of a plurality of plane surfaces, angularly disposed, and having sharp or well defined edges or corners at their junctures, the edges or corners extending vertically or longitudinally of the hosel and shaft.

We claim:

The ornamental design for a golf club as shown and described.
